DESIGN FOR A SCALE

Victor H. Menkhaus, Cincinnati, Ohio

Application February 9, 1942, Serial No. 105,725

Term of patent 14 years

To all whom it may concern:

Be it known that I, Victor H. Menkhaus, a citizen of the United States, residing at Cincinnati, in the county of Hamilton and State of Ohio, have invented a new, original, and ornamental Design for a Scale, of which the following is a specification, reference being had to the accompanying drawing, forming a part thereof.

I claim:

The ornamental design for a scale, substantially as shown.

VICTOR H. MENKHAUS.
